UNITED STATES PATENT OFFICE

167,216

ROTATABLE ILLUMINABLE CHRISTMAS TREE

Aubrey B. Leech, Los Angeles, Calif.

Application October 13, 1951, Serial No. 16,930

Term of patent 7 years

(Cl. D29—1)

To all whom it may concern:

Be it known that I, Aubrey B. Leech, a citizen of the United States of America, residing in the city of Los Angeles, in the county of Los Angeles, State of California, have invented a new, original, and ornamental Design for a Rotatable Illuminable Christmas Tree, of which the following is a specification, reference being had to the accompanying drawing, forming a part thereof:

Fig. 1 is a perspective view of a rotatable illuminable Christmas tree, showing my new design;

Fig. 2 is a side elevational view thereof;

Fig. 3 is a bottom view of the same;

I claim:

The ornamental design for a rotatable illuminable Christmas tree, substantially as shown.

AUBREY B. LEECH.
